DESIGN FOR A TRUCK TANK

Mason L. Thompson, Kansas City, Mo., assignor to Standard Steel Works, North Kansas City,
Mo., a corporation of Missouri

Application October 2, 1937, Serial No. 71,926

Term of patent 14 years

To all whom it may concern:

Be it known that I, Mason L. Thompson, a citizen of the United States, residing at Kansas City, in the county of Jackson, and State of Missouri, have invented a new, original, and ornamental Design for Truck Tanks, of which the following is a specification, reference being had to the accompanying drawings, forming part thereof.

Fig. 1 is a perspective view of a truck tank, showing my new design.

Fig. 2 is a plan view of the truck tank.

Fig. 3 is a rear end view of the truck tank.

Fig. 4 is a side elevational view of the truck tank.

I claim:

The ornamental design for a truck tank, as shown.

MASON L. THOMPSON.
